UNITED STATES PATENT OFFICE

158,668

ANTISKID JACKET FOR PNEUMATIC TIRES OR SIMILAR ARTICLE

Chester R. Kennedy, Lakeville, Mass.

Application January 18, 1949, Serial No. 292

Term of patent 14 years

(Cl. D90—20)

To all whom it may concern:

Be it known that I, Chester R. Kennedy, a citizen of the United States of America, residing at Clearpond Road, Lakeville, county of Plymouth and Commonwealth of Massachusetts, have invented a new, original, and ornamental Design for Anti-Skid Jacket for Pneumatic Tires or Similar Article, of which the following is a specification, reference being had to the accompanying drawings, forming a part thereof.

Fig. 1 is a side view of an anti-skid jacket for pneumatic tires or similar articles, showing my new design;

Fig. 2 is a fragmentary side view thereof drawn to larger scale; and

Fig. 3 is a top plan view of Fig. 2.

I claim:

The ornamental design for an anti-skid jacket for pneumatic tires or similar article, substantially as shown.

CHESTER R. KENNEDY.
